AMMUNITION

Harold M. Brayton, Teaneck, N. J.

Application September 19, 1934, Serial No. 744,726

5 Claims. (Cl. 102—12)

The invention relates to improvements in ammunition and more particularly to means for holding the impelling powder on the projectile.

One of the main requirements for modern weapons is to obtain the maximum possible range for the projectile. In certain classes of weapons, it is also very necessary that provision be made whereby the operator can vary the impelling powder charge at will, thus permitting him to select different muzzle velocities and therefore different ranges for the projectile.

Ammunitions heretofore employed in the art have possessed limitations and defects making them incapable of fully and completely meeting service requirements.

My invention aims to provide a new and improved ammunition permitting the incorporation of a much larger quantity of impelling powder and permitting easy removal of one or more increments of this powder, at the same time securely holding the capsules containing the increments in place for transportation and handling.

With the foregoing in view, the invention resides in the novel subject matter hereinafter described and claimed, description being accomplished by reference to the accompanying drawings.

Fig. 1 is a side elevation showing one form of the invention.

Fig. 2 is a rear end view.

Fig. 3 is a transverse sectional view on line 3—3 of Fig. 1.

Fig. 4 is a side elevation showing a different construction.

Fig. 5 is a detail side elevation similar to a portion of Fig. 1, but showing a slightly different construction.

Preferred structures have been illustrated and will be rather specifically described, with the understanding however, that numerous variations may be made within the scope of the invention as claimed.

A tubular cylindrical tail member 10 (Figs. 1, 2 and 3) is suitably secured at 11 to the reduced rear portion 12 of a projectile 13 whereas in Fig. 4 a much longer tubular tail member 10^a is shown secured at 11^a to the rear of the projectile 13^a. Radial longitudinally extending fins 14 are secured to the member 10 or 10^a, those of the member 10 being about co-extensive in length therewith whereas those shown in Fig. 4 are considerably shorter than the member 10^a. Capsules containing the increments of impelling powder are placed between the fins 14 and are so held therein that any number of said capsules

may readily be removed. The capsules are given the number 15 in most views, in which they are somewhat shorter than the fins 14. In Fig. 4, however, the capsules are shown at 15^a and they project forwardly from said fins around the front 5 portion of the tail 10^a.

In the present disclosure, each fin 14 is provided with a deep notch 16 opening through its outer edge and extending from a point near the rear end of the fin to a point near the front end 10 thereof, and is provided also with a plurality of long slender longitudinally spaced fingers within said notch. Some or all of these fingers are bent laterally to hold the capsules 15 or 15^a against radial movement from engagement with 15 the fins 14. When removing any of the capsules 15, if said capsules be sufficiently yieldable, the fingers 17 need not be molested, but if removal of capsules can be facilitated by bending said fingers, this can readily be accomplished. The long slender formation of the fingers 17 and the spacing thereof, insure that they shall not interfere with passage of propulsion gases through the notches 16 at the moment of firing, said passage being essential for best results.

Any suitable means may be provided for holding the capsules against longitudinal sliding. Preferably, fingers 18 are bent laterally from the rear ends of the fins 14 to abut the rear end-facing surfaces of the capsules. In the form of construction shown in Fig. 1, the front ends of the fins 14 are formed with openings 19 through which to pass a cord or the like 20 so that it abuts the front end-facing surfaces of the capsules 15 to hold them against forward sliding. When removed capsules, the cord may be cut and withdrawn if desired and it is not necessary to insert another cord or the like before loading the weapon.

In Fig. 5, the front ends of the fins 14 are 45 provided with bendable fingers 21 to abut the capsules 15, holding them against forward sliding.

When the capsules project forwardly beyond the fins as shown in Fig. 4, suitable provision is made for connecting the front ends of the capsules with the projectile. In the present disclosure, the capsules 15^a are provided with forwardly projecting fingers 22 lying against the projectile tail portion 10^a and secured against the same by a cord or the like 23. When removing a capsule, its finger 22 may be withdrawn from under the cord or the like 23.

Ignition of the impelling powder in the capsules may be accomplished in any desired manner. In the structure herein disclosed, the 60

central tubular member 10 or 10^a is adapted to receive a specially loaded cartridge 24 carrying a small primer 25 in its head to be fired by a firing pin in the weapon. It is possible however, to incorporate a separate primer in the rear of the weapon and to ignite the powder in the capsules directly from it through an auxiliary igniter. When the structure herein disclosed is followed, the tubular member 10 or 10^a is provided with 10 flame openings 26 positioned between the fins 14, allowing the flame from the cartridge 24 to reach the capsules 15 or 15^a which are of course combustible. The cords or the like 20 and 23 and the fingers 22 are likewise formed of combustible material.

To facilitate manufacture, the fins 14 are preferably formed in pairs connected by webs 27, said webs of course having openings such as 28 registering with the openings 26. The fins may well 20 be secured to the members 10 or 10^a by welding, as denoted at 29 in a number of the views.

The invention can, of course, be applied to ammunition for any caliber of weapon and any 25 number of capsules containing the increments of powder, may be used. The cross section of the capsules may be of any desired form and said capsules may be of any appropriate length. Preferably six capsules are used with their axes 30 parallel to the longitudinal axis of the projectile.

30 The present invention is not concerned with stabilizing the projectile during flight and this may, of course, be accomplished in any appropriate way. Moreover, the invention is obviously not restricted to use in any particular kind of 35 weapon. Then too, the structural features which have been shown for illustrative purposes, may be varied within the scope of the invention as claimed.

I claim:

40 1. A projectile having radial fins, capsules of impelling powder extending longitudinally between said fins and projecting forwardly therefrom, means for holding said capsules between said fins, fingers secured to and projecting forwardly from said front ends of said capsules, and a tie surrounding said fingers and securing the front ends of said capsules in place.

2. A projectile having radial fins, rearwardly 50 located capsule-abutting means extending transversely of the rear ends of said fins, forwardly located capsule-abutting means extending transversely of the front ends of said fins, elongated capsules of impelling powder disposed longitudinally between said fins and of no greater length than the distance between said forwardly and 55

rearwardly located capsule-abutting means; the end-facing surfaces of said capsules being disposed against said capsule-abutting means to positively hold the capsules against longitudinal sliding between said fins, and means for holding said capsules against radial movement from said fins; at least one of said capsule-abutting means consisting of fingers bent laterally from said fins.

3. A projectile having radial fins, rearwardly located capsule-abutting means extending transversely of the rear ends of said fins, forwardly located capsule-abutting means extending transversely of the front ends of said fins, elongated capsules of impelling powder disposed longitudinally between said fins and of no greater 10 length than the distance between said forwardly and rearwardly located capsule-abutting means, the end-facing surfaces of said capsules being disposed against said capsule-abutting means to positively hold the capsules against longitudinal 15 sliding between said fins, and means for holding said capsules against radial movement from said fins; one of said capsule-abutting means consisting of fingers bent laterally from said fins, the other of said capsule-abutting 20 means consisting of a cord passing through 25 openings in said fins.

4. A projectile having a long tail and radial fins at the rear end of said tail, capsules of impelling powder extending longitudinally between 30 said fins and projecting forwardly therefrom around the front portion of said tail, means for holding said capsules between said fins, fingers secured to and projecting forwardly from the front ends of said capsules, said 35 fingers lying against the front portion of said tail, and a tie surrounding said fingers and securing them against said front portion of said tail.

5. A projectile having radial fins between 40 which to place capsules of propelling powder, forwardly located capsule-abutting means extending transversely of the front ends of said fins, rearwardly located capsule-abutting means extending transversely of the rear ends of said 45 fins, and means for holding the capsules against radial movement from the fins, said forwardly and rearwardly located capsule-abutting means being positioned to abut forwardly and rearwardly facing end surfaces of the capsules, at 50 least one of said capsule-abutting means consisting of fingers bent laterally from said fins.

HAROLD MORGAN BRAYTON. 55
